UNITED STATES PATENT OFFICE.

WILLIAM S. HALSEY, OF PITTSBURG, PENNSYLVANIA.

GAS-ENGINE.

SPECIFICATION forming part of Letters Patent No. 659,027, dated October 2, 1900.

Application filed February 1, 1900. Serial No. 3,566. (No model.)

To all whom it may concern:

Be it known that I, WILLIAM S. HALSEY, of Pittsburg, in the county of Allegheny and State of Pennsylvania, have invented a certain new and useful Improvement in Gas-Engines, of which improvement the following is a specification.

The object of my invention is to provide an internal-combustion motor of simplified and comparatively-inexpensive construction in which a compression and an explosion of the mixture of gas and air shall be effected at each revolution of the shaft and the products of combustion shall be effectively discharged from the cylinder after each working stroke of the piston.

To this end my invention, generally stated, consists in the combination of a cylinder having a solid or imperforate wall between its end ports, a piston working therein, admission-valves controlling the supply of a mixture of gas and air to one end of the cylinder, an independent exhaust-valve controlling the discharge of products of combustion from the opposite end of the cylinder, and a supply-valve controlling a passage through the piston for the traverse of compressed charges of a mixture of gas and air from the suction side of the piston to the pressure side thereof.

The improvement claimed is hereinafter fully set forth.

In the accompanying drawings, Figure 1 is a side view in elevation of a gas-engine embodying my invention with the cylinder and valve-casings in section on the line *a a* of Fig. 3; Fig. 2, a view in elevation as seen from the opposite side; Fig. 3, a vertical transverse section through the cylinder and exhaust-valve casing on the line *b b* of Fig. 1; and Fig. 4, a vertical longitudinal section, on an enlarged scale, through a portion of the cylinder and the admission-valve casing.

In the practice of my invention I provide a suitable frame or bed-plate 1, upon one end of which a main or crank shaft 2 is supported in bearings in the ordinary manner and to the other end of which is secured a cylinder 3, which is surrounded by a water-jacket 4. The shell or wall of the cylinder is solid or imperforate between the admission and exhaust ports at its opposite ends, hereinafter

specified, and it is closed at its end farther from the crank-shaft by a removable head 5, and its opposite end is closed by a head 6, 55 which is preferably formed integral with the bed-plate 1, as indicated in Fig. 1. A piston 7 is fitted to traverse longitudinally in the cylinder 3 and is secured upon a piston-rod 8, the opposite end of which is secured to a 60 cross-head 9, traversing on guides 10 on the bed-plate and carrying a pin 11, which is coupled by a connecting-rod 12 to a crank-pin 13 on a crank disk or arm 14, fixed upon the crank-shaft 2. 65

An admission-valve casing 15 is formed upon or fixed to the cylinder 3 at its end adjacent to the crank-shaft, said casing communicating with the cylinder by an admission-port 16, and an exhaust-valve casing 17 70 is secured to the opposite end of the cylinder and communicates therewith by an exhaust-port 18. A gas-supply pipe 19, leading from any suitable source of gas-supply, opens into the admission-valve casing 15 and communicates with a valve-cage 20, secured removably therein through ports on the valve-cage. A passage 21, leading to the atmosphere, is formed in the outer end of the valve-cage 20 and is controlled by an upwardly-opening air-admission valve 22, which is normally held seated by a spring 23. The interior of the valve-cage communicates with the admission-port 16 by a passage 24, controlled by an upwardly-opening check-valve 85 25. A lateral nozzle or passage 26 for the connection of an exhaust-pipe leading to a desired point of discharge is formed upon the side of the exhaust-valve casing 17, and communication between said passage and 90 the exhaust-port 18 is controlled by an upwardly-opening exhaust-valve 27, fixed upon a stem 28. The outer end of the exhaust-valve stem 28 carries a pin 29, which fits in a cam-groove 30, formed in a bar 31, which is 95 fitted to traverse in a guide 32 on the outer end of the valve-casing 17. The bar 31 is journaled to one end of a double-armed rocking lever 33, which is centrally pivoted on the water-jacket 4, and the opposite end of the rocking lever is coupled to an eccentric-rod 34, which is secured to the strap 35 of an eccentric 36, fixed upon the crank-shaft 2. A supply-valve 37, which opens in the direc-

tion of the cylinder-head 5 and is normally held seated by a spring 38, controls a passage 39, leading from one side of the piston to the other. A fly-wheel 40 is secured upon 5 the crank-shaft 2, and the engine is provided with any suitable known igniting device—as, for example, an igniting-tube 41, located in position to fire a charge on the outer or left-hand side of the piston 7.

10 In the operation of a motor embodying my invention the movement of the piston 7 to the left, which is effected by the momentum of the fly-wheel 40, draws in air through the passage controlled by the air-admission valve 15 22, and gas is supplied through the gas-supply pipe 19. The air and gas commingle in the interior of the valve-cage 20, and the resultant mixture passes through the port governed by the check-valve 25 and through the 20 inlet-port 16 into the cylinder on the right-hand or suction side of its piston 7. Assuming a compressed charge of a mixture of gas and air to have been previously supplied to the clearance-space on the left-hand or pressure 25 side of the piston, as presently to be described, such charge is exploded and burned by the igniting device 41, and the resultant expansion of the charge effects the working or right-hand stroke of the piston, which, 30 through its connections, correspondingly rotates the crank-shaft 2 and fly-wheel 40. In making its working stroke the piston initially compresses the mixture of gas and air which has been previously admitted to the 35 cylinder on the right-hand or suction side of the piston until the pressure of said mixture becomes equalized with that of the products of combustion on the left-hand or pressure side of the piston, whereupon the supply-valve 27 is unseated and the charge in the cylinder on the suction side of the piston passes through the opening therein to the pressure side thereof. At or about the 40 period of such equalization the exhaust-valve 27 is unseated through its connections with the eccentric 36, and the burned gases are expelled through the exhaust-port 18 and passage 26 by the charge of unburned mixture, which passes to the pressure side of the piston 45 through the passage 39 therein. It will be seen that as the supply-valve 37 opens or unseats automatically when the pressures on opposite sides of the piston become equalized the remainder of the working or right-hand stroke of the piston is effected without back pressure. During the working stroke of the piston the check-valve 25 and air-admission valve 22 are closed by the pressure on their upper sides, and compression of the gas 50 in the supply-pipe 19 or leakage thereof to the atmosphere is thereby prevented. In the succeeding left-hand or compression and suction stroke of the piston the initially-compressed charge of a mixture of gas and air 55 which has been supplied to the pressure side of the piston during the preceding working stroke is further and finally compressed on

that side of the piston until the piston reaches the limit of its left-hand traverse, when the charge is ignited and another working stroke 70 of the piston is effected. Gas and air for the next succeeding working stroke are drawn into the cylinder on the suction side of the piston during the left-hand stroke thereof, as first above described. 75

My invention presents in practice the substantial advantages of enabling a working impulse to be exerted at each revolution of the shaft, of relieving the piston from objectionable back pressure during its working stroke, 80 and of fully and effectually discharging the burned gases and residuum of combustion from the cylinder after each working stroke. 85

I claim as my invention and desire to secure by Letters Patent— 85

1. In an internal-combustion motor, the combination of a cylinder having an admission-port at one end and an exhaust-port at the other, and having its wall solid or imperforate between said ports, a piston working 90 in said cylinder, admission-valves controlling the supply of a mixture of gas and air to the admission-port, an independent exhaust-valve controlling the discharge of products of combustion from the exhaust-port, and a 95 supply-valve controlling a passage through the piston for the traverse of initially-compressed charges of a mixture of gas and air from the suction side of the piston to the pressure side thereof. 100

2. In an internal-combustion motor, the combination of a cylinder having an admission-port at one end and an exhaust-port at the other, and having its wall solid or imperforate between said ports, a piston working 105 in said cylinder, a crank-shaft and fly-wheel connected to and rotatable by the piston, means for automatically effecting the supply of a mixture of gas and air to the admission-port, means, actuated from the crank-shaft, for releasing products of combustion from the exhaust-port, and an automatically-operating supply-valve, controlling a passage through the piston and affording traverse for a charge of a mixture of gas and air from the 115 suction to the pressure side thereof, coincidentally with the release of the products of combustion from the pressure side. 120

3. In an internal-combustion motor, the combination of a cylinder having an admission-port at one end and an exhaust-port at the other, and having its wall solid or imperforate between said ports, a piston working 125 in said cylinder, a crank-shaft and fly-wheel connected to and rotated by the piston, an admission-valve casing, communicating, by the admission-port, with the cylinder, on the suction side of the piston, a gas-supply pipe leading into said casing, an air-admission valve controlling an air-inlet to said casing, 130 a check-valve controlling communication between said casing and the admission-port, an exhaust-valve casing having a discharge-passage and communicating, by the exhaust-port,

with the opposite end of the cylinder, an exhaust-valve controlling communication between said casing and the exhaust-port, connections with the crank-shaft, through which
5 said exhaust-valve is unseated coincidently with the compression of a charge of mixed gas and air by the piston, and a supply-valve

controlling a passage through the piston and opening toward the exhaust-valve.
